UNITED STATES PATENT OFFICE

VICTOR WEINGARTNER, OF ST. ALBANS, NEW YORK, ASSIGNOR TO ROBERTS, CUSHMAN & COMPANY, INC., OF NEW YORK, N. Y., A CORPORATION OF NEW YORK

MARKING, PRINTING, AND EMBOSSED MACHINE

Application filed June 10, 1932. Serial No. 616,395.

This invention relates to marking, printing and embossing machines, and has for its general object and purpose to provide such a machine for printing or embossing plain or lustrous letters, designs, emblems or other identifying indicia upon articles composed in whole, or in part, of leather, fiber paper, textile fabrics or other analogous materials.

As the various articles upon which the machine is designed to operate may more or less vary in thickness, it is the principal object and purpose of my present improvements to provide simple, easily operated and effective means whereby the ultimate printing 10 position of the type elements relative to the impression receiving surface of the article may be adjusted in accordance with such variations in thickness of the articles, so that the depth of such impressions shall be uniform, 15 irrespective of such thickness variations, whereby possible injury or damage to the article is avoided, and the letters or other printed impressions are in all cases clearly visible and legible.

It is also an object of my present invention 20 to provide a device for accomplishing the above result which consists of very few simply constructed parts capable of ready application to such marking or embossing machines 25 now in general use and without materially increasing the manufacturing cost thereof.

With the above and other objects in view, the invention consists in the improved marking, printing or embossing machine, and the 30 combination and arrangement of the several elements constituting the essential features of my present invention, as will be hereinafter more fully described, illustrated in the accompanying drawing and subsequently incorporated in the subjoined claims.

In the drawing wherein I have illustrated 35 one simple and practical embodiment of the device and in which similar reference characters designate corresponding parts throughout the several views.

Figure 1 is a side elevation of one type of marking or embossing machine having a preferred form of my invention applied thereto;

Fig. 2 is a plan view as indicated by the line 2-2 of Fig. 1;

Fig. 3 is an enlarged sectional view taken on the line 3-3 of Fig. 2; and

Fig. 4 is a fragmentary detail section of certain of the parts shown in Fig. 3.

For the purpose of illustration, I have 55 shown my present invention as applied to a marking or embossing machine of that general character upon which numerous patents have hereto been issued to Max A. G. Luedtke and Hugo Hoffmann. More particularly, in 60 the drawing I have illustrated substantially the same machine as is shown in the pending application of these inventors, Serial No. 375,613, filed July 3, 1929, and in which a single type carrying disc or wheel is rotatably supported in a casing or housing, said 65 housing being pivotally mounted on a base so that together with the wheel it may be vertically moved or oscillated towards and from an article supporting platen or carriage.

With this movable type wheel or disc, there is associated means for automatically feeding a tape or strip coated with metallic foil between the wheel and the platen so as to present a new portion of the 70 tape for each impression. For the purpose of the present explanation, a general reference to this machine of the above application will suffice. Thus, upon reference to the drawing, it will be seen that the housing or casing 5 for the rotatably adjusted wheel or disc 6 is suitably mounted at its lower end upon a horizontal axis supported on the base 7, said wheel upon its periphery being 75 provided with the circumferentially spaced type elements shown at 8. In the present instance, each of these type elements is secured to or integrally formed with teeth or projections 9 on the periphery of the disc.

While my present invention, as will be 80 85 90

evident from the following detailed description thereof, might be applied to a machine of this kind having a stationary bed or support for the article, in the illustrated application thereof, I have shown the device applied to the movable platen or work support generally indicated at 10 which is suitably mounted and arranged upon the forwardly projecting arm 11 of the base 7 for horizontal sliding movement in a plane parallel with the axis of oscillation of the housing 5 and wheel 6. Mechanism is provided similar to that shown in the referred to pending application for imparting a step by step movement to this carriage or platen in the successive printing of the letters. It will, however, be clear that any other suitable means for this purpose might be utilized.

The carriage 10 is provided along its forward edge with an upstanding longitudinal rib or ledge indicated at 12, and which provides the supporting surface for that part of the article which receives the impressions from the type elements 8. Any suitable means might be attached to this sliding carriage to project forwardly therefrom for the purpose of supporting and positioning the article as a whole and holding the same against shifting movement relative to the carriage. Since this, however, constitutes no essential part of the present invention, it is not herein shown or described in detail.

Upon the carriage 10, a gauge device is mounted for the purpose of limiting the depth of the impressions made by the type members 8 in the surface of the article. In the present instance, I have shown this gauge device as consisting essentially of a metal plate 13 of general rectangular form and provided at the opposite ends thereof adjacent its rear longitudinal edge with the ears 14, which are pivotally attached as at 15 to opposite ends of the sliding carriage or platen. The other or forward edge of this gauge plate is preferably bevelled downwardly from its upper surface as indicated at 16, and adjacent to said bevelled edge of the plate the same is provided with the longitudinally extending slot 17. Rearwardly of this slot, spaced downwardly projecting pins or studs 18 are fixed at their upper ends to said plate and constitute stop means with which the article indicated at A inserted beneath the gauge plate contacts, as clearly shown in Fig. 3 of the drawing. Rearwardly of the pivots 15 for the gauge plate, a plurality of longitudinally spaced coil springs 19 are interposed between the gauge plate and the carriage or platen 10, so that said springs by their expansive action tend to rock the gauge plate upon the carriage and yieldingly hold its bevelled edge 16 in contact with the rib or ledge 12, as shown in Fig. 1 of the drawing.

The gauge plate 13 at one end thereof is

formed with a laterally and rearwardly projecting finger-piece 20 which is inclined upwardly at a slight angle with respect to the plane of the plate 13 and provides a convenient means whereby said plate may be rocked or oscillated upon its pivots 15 against the action of the springs 19, so as to lift or elevate its forward edge 16 sufficiently to permit of the insertion of the article A between said plate and the rib or ledge 12 on the carriage.

When the machine is used for printing or marking plain ink impressions on the material, any suitable form of inking device may be provided within the housing 5 for inking the faces of the type elements 8 as the disc 6 is rotated. When lustrous letters or other impressions are to be made, a metallic foil carrying strip is suitably mounted for movement between the letter wheel and the article supporting carriage or platen. This strip or tape which I have illustrated at 21 is also fed by a step by step movement in the oscillations of the letter wheel as the successive impressions are made. While various mechanisms might be devised for effecting this movement of the tape, I preferably use such a mechanism as is shown in the pending application above referred to, and which has been found highly efficient and serviceable in machines of this type.

Having above described the several mechanical parts of my present improvement, upon reference to Fig. 3 of the drawing, it will be noted that when the gauge plate 13 is in superimposed relation to the article A extending rearwardly from the ledge 12 of the carriage, the forward bevelled edge 16 of said plate projects slightly beyond the vertical plane of the rear edge of said ledge or rib 12. When the wheel 6 is moved forwardly and downwardly to printing position, with the tape 21 interposed between a type element 8 and the surface of the article, said type element engages the article immediately in advance of the forward edge of the plate 16 and the corner or shoulder of the lug 9, from which said type element projects by contact with the bevelled surface 16 of the plate, limits the depth of the impression made by the type element in the surface of the article. It will also be noted that an adjacent type element 8 on the disc enters the slot 17 in the gauge plate. Contacting engagement of said lug upon said bevelled surface is immediately noticeable, both audibly and by reason of the additional resistance to any further downward movement of the type wheel. When an article of greater thickness is to be operated upon, the forward edge of the gauge plate is elevated by depressing the finger extension 20 so that the edge 16 of said plate will be disposed for a greater distance above the surface of the rib or ledge 12. Thus, this bevelled edge of the plate will in the same

manner limit the downward movement of the type wheel, so that the depth of the impression which is made in the surface of said article will be the same as in the case of the 5 article of less thickness. Therefore, it will be evident that by means of my present improvements, absolute uniformity in the depth of the impression is obtained regardless of the thickness of the material or article which 10 is operated upon, so that in the case of the thicker articles, the impressions will not be of such considerable depth as to impair the easy legibility of the printed impressions, or to possibly result in damage or injury to the 15 material.

From the foregoing description considered in connection with the accompanying drawing, it will be seen that I have provided a very desirable improvement in such marking 20 or embossing machines, and one which by reason of its simplicity, may be readily adapted or applied to such machines as are now in general use in the art. Also, it will be evident that the gauge device as herein disclosed 25 may be very easily and quickly operated and the article properly positioned with relation thereto so that it will function in a reliable and efficient manner to accomplish its intended purpose. I have herein shown and 30 described a preferred mechanical form of my present improvements which I have found from actual use is best designed to achieve my intended purpose. It is, nevertheless, to be understood that insofar as the essential characteristics of my present invention is concerned, the same may also be exemplified in 35 various other alternative structural forms, and I accordingly reserve the privilege of resorting to all such legitimate changes there- 40 in as may be fairly embodied within the spirit and scope of the invention as claimed.

I claim:

1. In a machine of the character described, 45 an article support, a plurality of type elements and means for selectively engaging said elements with an article on the support, and means associated with the support and directly cooperating with a part of said first named means to obtain a uniform contact 50 pressure of the type elements upon articles of varying thicknesses.

2. In a machine of the character described, 55 an article support, a plurality of type elements and means for selectively engaging said elements with an article on the support, a gauge device, and means for effecting relative adjustment between said gauge device and the support to position said gauge device relative to the article for cooperation with 60 a part of said means to limit contact pressure of the type elements upon the article.

3. In a machine of the character described, 65 an article support, a plurality of type elements and means for selectively engaging said type elements with an article on the sup-

port, and a manually adjustable gauge device on the support cooperating with a part of said means to limit contact pressure of the type elements upon the article.

4. In a machine of the character described, 70 a support, a plurality of type elements and means for selectively engaging said elements with the surface of an article of flexible material arranged on said support, a gauge device, and means for effecting relative adjustment between said gauge device and the support to position said gauge device relative to the article and for contact with a part of said first named means to obtain a uniform contact 75 pressure of the type elements upon articles of varying thicknesses.

5. In a machine of the character described, 80 an article support, a plurality of type elements and means for selectively engaging said elements with an article on the support, a gauge device movably mounted on the support, and means for yieldably retaining said gauge device in an adjusted position relative to the support and in superimposed contact 85 with the article for engagement by a part of said first named means to limit contact pressure of the type elements upon the article.

6. In a machine of the character described, 90 an article support, a plurality of type elements and means for selectively engaging said elements with an article on the support, a gauge plate movably mounted on the support for manual adjustment relative thereto and in superimposed relation to the article, 95 spring means yieldingly holding said plate in its adjusted position with an edge thereof cooperating with a part of said first named means to limit contact pressure of the type elements upon the article.

7. In a machine of the character described, 100 an article support having an upstanding rib upon which the article is adapted to be positioned, a plurality of type elements and means for selectively engaging said elements with a part of an article positioned on said 105 rib, a gauge plate pivotally mounted on said support for manual adjustment to be disposed in superimposed relation upon the article and with an edge thereof overlying said rib, and spring means coacting with the gauge plate to yieldingly retain the same in an adjusted position, said edge of the gauge plate cooperating with a part of said first named means to limit contact pressure of the 110 type elements upon the article.

8. In a machine of the character described, 115 an article support having an upstanding rib upon which the article is adapted to be positioned, a plurality of type elements and means for selectively engaging said elements with the part of an article positioned on said rib, a gauge plate pivotally mounted on said support for manual adjustment to be disposed in superimposed relation upon the article and with an edge thereof overlying said 120

rib, stop means secured to said gauge plate in spaced relation to said rib for contact with the article to limit movement to said article in one direction between the gauge plate and the support, and spring means coacting with the gauge plate to yieldingly retain the same in an adjusted position, said edge of the gauge plate cooperating with a part of said first named means to limit contact pressure of the type elements upon the article.

In testimony that I claim the foregoing as my invention, I have signed my name hereto.

VICTOR WEINGARTNER.
